COMBINED STEP-STOOL AND BOOKRACK

Judith L. Gilman, Iroquois Ave.,
Palisades, N.Y. 10964

Filed Apr. 24, 1967, Ser. No. 6,870

Term of patent 14 years

(Cl. D15—8)

FIG. 1.

FIG. 2.

FIG. 1 is a right front top perspective view showing the combined step-stool and bookrack of this invention; and

FIG. 2 is a left front top perspective view showing the step-stool of this invention as further modified by the omission of the handles shown in FIG. 1.

The back of the combined step-stool and bookrack is plain and unornamented. The books shown in dotted lines in FIGURE 1 are for illustrative purposes only.

I claim:

The ornamental design for a combined step-stool and bookrack, as shown and described.
